UNITED STATES PATENT OFFICE.

WILLIAM L. BUNKER, OF LA GRANGE, ILLINOIS.

DESIGN FOR A BICYCLE-SADDLE.

SPECIFICATION forming part of Design No. 25,725, dated June 30, 1896.

Application filed November 6, 1894. Serial No. 528,093. Term of patent 14 years.

To all whom it may concern:

Be it known that I, WILLIAM L. BUNKER, of La Grange, Cook county, Illinois, have invented and produced a new and original Design for Bicycle-Saddles, of which the following is a specification, reference being had to the accompanying drawings, forming a part hereof.

In the accompanying drawings, Figure 1 represents a front elevation of my design; Fig. 2, a plan view of the same, looking at it from the top; and Fig. 3 a transverse section taken through the central portion of the saddle.

The leading feature of my design consists in a substantially crescent-shaped body portion when viewed in elevation, double convex when viewed in plan view, and of curved contour when viewed transversely.

A is the main portion, substantially crescent-shaped in elevation, double convex in plan view, as shown in Fig. 2, and substantially circular, as shown in transverse section in Fig. 3; B, a supporting portion, and C a socket-piece by which the saddle may be secured in the desired place—the whole presenting to the eye a harmonious and ornate figure, substantially as illustrated in the drawings.

What I claim is—

The design for a bicycle-saddle herein shown and described.

WILLIAM L. BUNKER.
